UNITED STATES PATENT OFFICE.

GILBERT DIXON RAINÉ, JR., OF NEW YORK, N. Y.

NUMBER-BOARD FOR GOLFERS.

1,291,133.

Specification of Letters Patent. Patented Jan. 14, 1919.

Application filed November 26, 1917. Serial No. 203,943.

To all whom it may concern:

Be it known that I, GILBERT DIXON RAINÉ, Jr., a citizen of the United States, residing at New York, in the county of New 5 York and State of New York, have invented new and useful Improvements in Number-Boards for Golfers, of which the following is a specification.

The present invention relates to an indicator which is especially adapted for use 10 in connection with the conduct of golf tournaments or matches at which it may be employed as a call - board to indicate what player or team of players is due to start 15 play, that is to say, when a particular number is shown on the indicator the player or team to whom a corresponding number has been assigned will know that it is his or its turn to start in the game.

As is well known to those familiar with 20 golf, it is usual for a large number of the players to take part in a tournament, and it is also the practice, for the orderly conduct 25 of the same, to assign to each player, or team of players, a number which will indicate the order or turn in which the player or team is to start play. As golf courses 30 or grounds are necessarily extensive in area the players are likely, for one reason or another, to be located at widely separated points or places, while awaiting the call to 35 play, in some instances lounging about the clubhouse, or perhaps forming a part of the gallery and watching the play of a particular contestant. It also frequently happens that a player or team will fail to appear when due to play, and under such conditions delay usually occurs in notifying 40 later scheduled players that they must appear and start play sooner than they anticipated. Especially is this so when players are scattered about the grounds or clubhouses, and not expecting to be called before 45 a certain time. The delays incident to finding and starting the players are very annoying, create confusion and interfere with the orderly conduct of the tournament.

To obviate these objections and to insure 50 that players or teams will receive prompt notification when due to start play I have devised my improved indicator, which is of such character and may be so positioned or stationed on the grounds as to immediately and visually indicate, even to players or an 55 official located at relatively great distances,

what player or team is to take his or its turn in the game.

Another object of my invention is to provide an indicator-board of this character 60 which may be easily and instantly operated, and which will be plainly visible at relatively great distances, and which will embody in its construction the desired features of simplicity, efficiency and durability.

Another object of my invention is the provision of an indicator wherein the signal indicia, such as numerals, is to be exhibited or printed or otherwise marked upon a traveling web which is supported and stretched in such manner as to draw the web taut and 70 smooth at all times, thereby insuring the clear and plain exposition of the signal.

With the above recited objects and others of a similar nature in view, my invention 75 consists in the construction, combination and arrangement of parts set forth in and falling within the scope of the appended claims.

In the accompanying drawings:

Figure 1 is a perspective view of a preferred form of indicator embodying my invention.

Fig. 2 is a view partly in vertical longitudinal section and partly in elevation, with certain parts of the casing removed to show the interior arrangement.

Fig. 3 is a vertical cross-sectional view taken through the casing of the indicator.

Fig. 4 is an enlarged detail sectional view taken through the lower portion of the casing and the adjacent portion of the supporting standard or post.

Fig. 5 is a perspective view of one of the leaf springs acting as a brake plate.

Referring now to the accompanying drawings in detail, the letter A indicates the 95 standard or post of the device which may be of any suitable height and size, and which is surrounded by and supports the casing B of the indicator. This casing may also be of any preferred form, but is preferably constructed as shown herein, that is to say, embraces the bottom wall 1, a solid back wall 2 and a front wall 3 which is in the nature of an open frame forming the windows 4-4, preferably covered with glass, 100 as at 5, and through which windows the sign indicia, in the present instance numerals, may be exposed to view; a gable roof 6 constituting the top wall of the casing rests upon the beveled block 7 extending between 110

the upper ends of the end walls 8 of the casing, the upper ends of these walls 8 of course being oppositely beveled to conform to the contour of the gable roof and the block 7. In the present instance the casing is divided into two compartments by means of the upper section of the post A, and which section 9 is reduced in diameter and constitutes a bearing for the innermost studs 10 of the web rollers as hereafter described. I preferably employ four rollers, comprising two sets, the upper roller of each set being indicated by the numeral 10 while the lower roller of each set is shown at 11. 15 These rollers are of course spaced suitable distances apart, and one set of rollers occupies each of the compartments. Over each set of rollers travels a web 12 which may be formed of any suitable material, such as 20 fabric or the like, and is of sufficient dimensions to have a signal indicia printed thereon. In the present instance the indicia is in the nature of numerals shown at C, these numerals, as usual, preferably running 25 consecutively and are printed suitable spaces apart on the face of each web. Each roller is provided at its inner end with a relatively short stud 13 journaled in the upper section 9 of the post A and each section extends 30 vertically and interiorly of the casing, as before described, while the outer end of each roller is provided with a relatively long stud 14 extending through and finding a bearing in the adjacent end wall of the 35 casing. Each of these studs 14 is provided at its outer end with a hand wheel 15 so that its roller may be turned in the proper direction to cause a selected numeral to appear in the adjacent window or opening in 40 the front of the casing. For instance, when the hand wheels 15 of the uppermost rollers 10 are turned in the proper direction the webs will be drawn outward, while when the hand wheels 15 of the lowermost rollers are 45 turned in the proper direction the webs will be drawn downward. Obviously, by this arrangement the selected numerals may be caused to appear at their respective windows or openings. In this connection I 50 wish it to be understood that while I have shown two webs designed to be exposed through two windows or openings in the front of the casing, it will be evident that any number of webs may be employed. For 55 instance, if desired a single web coöperating with a single opening or window in the front of the casing may be used. In order to place a certain degree of tension upon the rollers and thus exert sufficient friction to 60 brake the rollers and thereby hold the webs in selected positions I provide each roller with a brake-plate 16 which is in the nature of a metallic leaf spring having a central opening 17 for the passage of the outer 65 stud of the adjacent roller, the brake-spring

having intermediate portions 18 bearing against the ends of the roller and end portions 19 bearing against the adjacent end wall of the casing, the springs being fastened by suitable screws 20 passing through screw openings 21, as will be best understood by reference to Figs. 3 and 5. These brake-springs exert constant friction on the rollers, as will be readily understood, and thus when a roller has been turned to a certain position, and the turn action ceases, the roller will remain at rest. 75

It is highly desirable that the portions of the webs exposed at the windows or openings in the front of the casing should be maintained taut and smooth, and that all wrinkles, creases and folds be avoided, this being particularly necessary when the sign is to be located so as to be observable from a considerable distance. To accomplish this 80 I provide a stretcher plate 22 which is fastened at its ends to strips or cleats 23 secured in turn to the interior faces of the end walls of the casing, the central portion of the stretcher plate being fastened to a filler 85 strip 24 attached to the upper section 9 of the post A. The top and bottom edges of the stretcher plate 22 are rounded as at 25, and as this stretcher plate is located in front of the rollers the webs wound on the rollers 90 are trained over the outer face of the stretcher plate so as to run between said plate and the openings or windows of the casing. Thus the stretcher plate 22, as best understood by reference to Fig. 3, will taunt 95 the webs and hold the same smooth or free from wrinkles or folds, thereby causing the numerals to be clearly and plainly exposed to view, when positioned at the windows or 100 openings of the casing. 105

If desired, for the sake of rigidity and strength, a filler strip 26 may be interposed between the rear wall of the casing and the section 9 of the post as best understood by reference to Fig. 4. 110

From the above description, taken in connection with the accompanying drawings, the construction and operation of my indicator will be readily understood. 115

Referring to Fig. 1, if for instance a player bearing the numeral 22 is to be called to take his turn in the game, the webs are turned by means of the hand wheels 15 until a numeral 2 appears at each window, thus indicating that player having the numeral 120 22 is called. As the numerals may be seen at a great distance, no time need be lost in sending calls or messages or otherwise notifying the player whose turn it is to play. 125

While I have herein shown and described one particular embodiment of my invention, I wish it to be understood that I do not confine myself to all the precise details of construction herein set forth by way of illustration, as modification and variation may 130

be made without departing from the spirit of the invention or exceeding the scope of the appended claims.

What I claim is:

- 5 1. An indicator of the class described comprising a supporting post, a casing mounted thereon through the central portion of which the upper part of the post extends dividing the casing into two sections, each
- 10 section having a window, a pair of spaced rollers located within each section of the casing and journaled at their outer ends in the end walls of the casing and at their inner ends in the said upper part of the supporting post, traveling webs mounted on said rollers and having signal characters thereon adapted to be exposed at the windows, and independent means for operating the said rollers to cause the webs to travel to expose
- 15 selected characters at the respective windows.
- 20 2. An indicator of the class described comprising a supporting post, a casing mount-

ed thereon through the central portion of which the upper part of the supporting post extends dividing the casing into two sections, said casing having a wall provided with a plurality of windows or openings, a pair of spaced rollers located within each section of the casing, and journaled at their outer ends in the end walls of the casing and at their inner ends in said upper part of the supporting post, traveling webs mounted on said rollers and having signal characters thereon adapted to be exposed at the openings, means for operating said rollers to cause the webs to travel to expose selected characters at the openings, a stretcher-plate underlying and bearing against the traveling webs to taunt such portions of the webs as are exposed at the openings, and supports for said stretcher-plate.

In testimony whereof I have hereunto set my hand.

GILBERT DIXON RAINÉ, JR.
